The ornamental design for a footboard for a scooter, as shown and described.

DESCRIPTION

FIG. 1 is a perspective view of a footboard of a scooter having circular regions that display contrasting colors of light emission on a rectangular foot-supporting side thereof;

FIG. 2 is a top view of the footboard of FIG. 1 showing the foot supporting side of the footboard, with vertical hatching indicating the color red and horizontal hatching indicating the color blue;

FIG. 3 is a perspective view of a second embodiment of a footboard of a scooter having circular regions that display contrasting colors of light emission on a rectangular foot-supporting side thereof; and,

FIG. 4 is a top view of the footboard of FIG. 3 showing the foot-supporting side of the footboard, with horizontal hatching indicating the color blue and cross-hatching indicating the color orange.

The portions of a scooter shown in broken lines in FIGS. 1-4, including wheels, handlebars, and mountings thereof, denote the environmental use of the claimed design, are for illustrative purposes only, and form no part of the claimed design.
